PUMP

Henry S. Hoffar, Vancouver, British Columbia, Canada, assignor to The Cleveland Pneumatic Tool Company, Cleveland, Ohio, a corporation of Ohio

Application June 27, 1944, Serial No. 542,364

17 Claims. (Cl. 255—45)

1

It is conventional practice to feed mining drills, such as diamond drills, by the use of a hydraulic piston and cylinder mechanism. Some such feed mechanisms can be operated either by compressed air or by liquid under pressure, but the latter type is preferred because of the more positive action and better control available. Moreover such drills may also be rotated during drilling by a fluid motor. An example of a drill incorporating such pressure fluid feed mechanism and air driven rotating motor is disclosed in my Patent No. 2,259,694, issued October 21, 1941, for Diamond drill feed control.

Compressed air is always available at a mine drill, supplied by a system of conduits, but if it is desired to operate the feed mechanism hydraulically a separate pump unit is provided for each drill to supply liquid under pressure. Such additional item has the disadvantage of constituting a further piece of equipment which must be moved when the drill is moved, and accommodated in the usually already cramped quarters where the drill is being used. The only alternative prior to my invention was to locate the pump at a distance from the drill, which necessitated additional supply lines. These are inclined to become tangled as the drill is moved for successive drilling operations.

To obtain the advantages of hydraulic drill feed mechanism without increasing the number of equipment pieces, I have devised pump mechanism which may be incorporated in an element of the drill assembly normally required for a drill incorporating air operated feed mechanism.

Customarily a drill is clamped upon a normally horizontal mine arm, which in turn is secured to an upright mine bar or post, usually extending between the roof and floor of a mine opening. When the mine bar is thus anchored the mine arm may be raised or lowered as desired and clamped to the mine bar to project laterally from it in any radial direction. The drill also may be shifted toward or away from the mine bar along the mine arm and clamped in any desired swiveled position when thus adjusted. By varying the relationship of these several mounting parts the drill can therefore be adjusted universally to drill a hole in a desired direction and at any selected location.

According to customary practice, therefore, the mine column and the mine arm are essential and conventional components of the drill assembly, being required to support the drill whatever type of drill feed and drive mechanism is provided.

2

It is a principal object of my invention to incorporate in the conventional mine bar or mine arm, and preferably the latter, hydraulic pump mechanism for supplying liquid under pressure which may be utilized to feed the drill, obviating the need for an accessory unit in addition to the components of the equipment ordinarily required.

A further advantage of pump mechanism incorporated in or carried by the mine arm or column is that, since the drill is mounted upon such arm, the pump and drill can always be close coupled, thus obviating long hydraulic lines which may become tangled.

15 An additional object of my invention is to provide pump mechanism which, while being incorporated in an element of the drill support, such as the mine arm, will not require any appreciable change in the customary dimensions of such element, yet the pump will be of adequate capacity to supply liquid under a pressure high enough and in sufficient quantity to feed the drill as rapidly as may be advantageous in performing the drilling operation. Moreover the liquid will 20 be supplied in a continuous stream the pressure of which does not fluctuate appreciably.

Still another object is to provide such hydraulic pump mechanism which can be driven by compressed air from the supply customarily available at a drill, and will not require any special source of power. Nevertheless it is an object to be able to accomplish regulation of the pump 30 operation easily at the will of the operator to vary the pressure and quantity of the liquid delivered by the pump, or to interrupt its operation.

Although the pump mechanism, because of the limited space available for housing it, must be exceedingly compact, it is not of intricate construction, nor are the parts delicate, so that the pump is reliable and does not require frequent repair, even when subjected to the rough usage which such equipment sometimes receives in mining operations. Despite such advantages the 40 pump elements may be fabricated readily and economically, and the entire assembly may be taken apart easily for repair or replacement of parts, if that should be necessary.

Other objects and advantages of my invention will be appreciated from a consideration of the following description of a preferred form of my pump. While the construction illustrated in the drawings has proven to be practical and has a number of advantages, it may be desirable in 50 some instances to modify certain of the parts,

or their location or arrangement, to satisfy special requirements.

Figure 1 is a side elevation view of a mine arm incorporating my invention, parts of which have been broken away to disclose the pump mechanism contained therein.

Figures 2, 3 and 4 are transverse sectional views through the mine arm and pump mechanism taken along lines 2-2, 3-3, and 4-4, respectively, of Figure 1, as viewed in the respective directions indicated by the arrows.

Figure 5 is a longitudinal sectional view through a portion of the mine arm, showing part of the pump structure in elevation, and Figure 6 is a transverse sectional view on line 6-6 of Figure 5.

Figure 7 is a diagrammatic view of the various elements of the pump assembly to illustrate the operational relationship and function of its several components.

As stated previously, it is preferred that the pump assembly be housed in the mine arm 1, particularly because it is usually disposed in a substantially horizontal position. It would be possible, however, to locate the pump mechanism in the mine column B anchored in upright position in the mine shaft, if that were preferred. The mine arm is supported in the conventional manner by a clamp 10 and positioning collar 11 secured upon the mine bar. The drill 2 in turn is secured in the desired position lengthwise of the mine arm by a clamp 20. The mounting cone 21 may be clamped between blocks 22 to hold the drill in any adjusted angular position, according to conventional practice.

The mine arm 1 is usually tubular, and in this instance likewise, of course, is hollow, but it has special features of construction to adapt it more conveniently for installation of the pump mechanism. Thus an annular shoulder integral with the inner surface of the mine arm forms an abutment 12 which divides its interior into a reservoir space 13 at the left end of the arm, as seen in Figure 1, and a pump mechanism housing space 14 within its right end. The left end of the mine arm may be closed by a cap 15, and its upper side has a filling opening 16 provided with a strainer and normally closed by a plug, as indicated in broken lines in Figure 1.

The pump mechanism is assembled into the space 14 within the right end of the mine arm, which is flanged for attachment to a mounting block 17 by machine screws 18. Abutment 12, engaged by the pump assembly, limits the extent of its movement into the arm. A set screw 19 fitting in a keyway along the upper side of the mechanism may be employed to establish the proper rotative position of the parts.

The pump itself is air driven, and is composed of only four principal parts. One of these is the stepped piston 3 constituting an element common to the hydraulic pump and to the air motor which drives the pump. This composite piston extends lengthwise within coaxial cylindrical bores formed in three cylindrical blocks 4, 5 and 6, also disposed coaxially. The bore in each block constitutes a cylinder for a different portion of the stepped piston. The central portion of the piston is the largest and slidably fits a cylindrical bore 50 in block 5, the axis of which is offset from the axis of the cylindrical block, as shown in Figure 3. The left end 30 and the right end 31 of the piston are of the same size, both being much smaller than its central portion, to form hydraulic pump plungers. At its junction with such plungers the enlarged central

portion of the piston has annular surfaces disposed in radial planes, constituting pressure faces against which air under pressure admitted to cylinder space 50 alternately at opposite sides of the enlarged portion of the piston may press to drive the piston for lengthwise reciprocation.

The piston plunger 30 is slidably received in a bore 40 in block 4, which constitutes one hydraulic liquid pump cylinder, while a similar bore 60 in block 6 slidably receives the other reduced end 31 of the piston and constitutes the second hydraulic pump cylinder.

The other main component of the pump assembly is the cylindrical valve block 7, which incorporates a rather conventional annular reversing valve 70, operable to control the supply of air to cylinder space 50 for reversing the direction of travel of piston 3 automatically at each end of its stroke.

Before discussing the preferred construction of the pump mechanism in further detail it will be helpful to have an understanding of the operative relationship and function of its various elements, which may be acquired most readily from the diagrammatic illustration of the system embodied in Figure 7.

Hydraulic liquid, such as oil, under operating pressure is supplied to the drill through a short flexible hose from a connection 23 communicating with the pressure duct P of the pump. Hydraulic liquid is returned from the pump through a second short flexible hose to the connection 24 leading into return duct R of the pump which communicates unobstructedly with reservoir 13. A supply duct S connects the reservoir with the pump cylinder spaces 40 and 60, in which the plunger ends 30 and 31, respectively, of piston 3 reciprocate. All of passages P, S and R extend through all of blocks 4, 5 and 6.

In addition, passages through valve block 7 and blocks 5 and 6 convey air between the valved passages and air cylinder 50 for the dual purpose of reciprocating piston 3 and automatically shifting valve 70 to effect such reciprocation. This valve, it will be noted, is of the sleeve type, and is guided for axial shifting by stepped, generally conical inserts 71 which seat in the ends of valve block 7 and are held together by a machine screw 72. Valve 70 is formed internally to slide on the shank of screw 72 and on cylindrical portions of inserts 71. Moreover the valve and such inserts are complementally shouldered to limit the endwise travel of the valve.

The external circumference of valve 70 has three lands spaced by two annular grooves. These lands and grooves cooperate with lands 73 on block 7 to form seals between the block lands and valve lands in registry and by-pass passages between adjacent block grooves around the intermediate block lands in registry with valve grooves. As the valve 70 is shifted from one end of its stroke to the other the valve grooves in registry with block lands forming by-pass passages around them will be moved out of registry with such lands to close such by-pass passages. By the same movement, however, such valve grooves will move into registry with other block lands forming different by-pass passages, which will direct the air flow through the valve mechanism to reverse the flow to air cylinder 50.

Air is supplied to the central groove of valve block 7 through a conduit 74 connected to an external source of air under pressure. With the parts in the position shown in Figure 7 piston 3 has just begun its travel to the right, as indi-

cated by the arrow. It is driven in this direction by air under pressure entering the central groove of valve block 7 from conduit 74, passing around the valve block land forming the right wall of such groove into the adjacent block groove on the right from which duct 51 leads, and moving through such duct in the direction of the arrow to the left end of air cylinder 50. Piston 3, forced to the right by such air pressure on the left annular surface of its enlarged central portion, scavenges air from the right end of air cylinder 50 through duct 53, which is connected to the right groove of valve block 7, and through duct 52 communicating with the groove of valve block 7 adjacent its central groove on the left. From the latter groove such air bypasses the valve block land forming the left wall of such groove, by way of the left groove of valve 70 in registry with such land, into the adjacent valve block groove on the left, and thence out to the atmosphere through a port 75 in the lower side of the block to the left of its center leading from such groove.

Air forced through duct 53 by the initial movement of piston 3 to the right passes into the groove of valve block 7 farthest to the right, to which the right end of sleeve valve 70 is exposed. Such pressure tends to hold the valve to the left in the position shown, although it is slight because air is bled from this block groove through a small aperture into the right duct 75 which leads to the atmosphere. Flow through duct 53 does not continue for long, because its opening into air cylinder 50 is uncovered just before the piston 3 reaches the end of its stroke to the left, and consequently is again covered almost immediately after the commencement of the piston's stroke to the right. Throughout such stroke, however, the piston continues to force air from the right end of air cylinder 50 through duct 52.

The central portion of valve 70 sliding on bolt 72 interconnecting inserts 71 is considerably shorter than the spacing between the inner ends of such inserts. Ports 76 extend through the valve wall to establish communication between the respective valve grooves and the corresponding spaces at opposite sides of the central inwardly projecting annular rib of the valve. The end surfaces 71 of such annular rib constitute piston areas which are also utilized to assist in maintaining the valve in its proper position even after passage 53 has been closed by piston 3.

With the valve in the position shown, therefore, it will be seen that the right port 76 is in communication with the central block groove and the groove adjacent to it on the right, through which grooves flows air under pressure from conduit 74. Such compressed air is admitted to the right piston surface 77 of the valve by way of right port 76, which will hold the valve at the left end of its stroke since the left valve piston surface 77 is in communication with the atmosphere through the left port 76 and the valve block groove with which the left atmospheric port 75 communicates.

During movement of piston 3 to the right, the volume of the left hydraulic liquid cylinder 40 will be increased by the withdrawal of piston stem 30 from it. Such volumetric expansion will draw oil from the reservoir 13 through the portion of supply duct S in block 4 and past a check valve 41 into hydraulic cylinder 40. Simultaneously the volume of the other hydraulic liquid cylinder 60 in block 6 will be decreased by move-

ment of plunger 31 into it. The oil in this cylinder, filled during the immediately previous stroke of piston 3 to the left, cannot pass back through the supply duct S in block 6 to the reservoir 13 past check valve 61. The pressure exerted on this oil by piston plunger 31 therefore forces open check valve 62 in pressure duct P. Such pressure, reacting through the portions of duct P in blocks 4 and 5 also holds check valve 42 closed, and the oil under pressure is delivered through hose connection 23 to the pressure side of the drill feed mechanism.

As piston 3 nears the end of its stroke toward the right, which position of the piston is indicated by broken lines, it will be seen that the end of duct 54 communicating with air cylinder 50 will be uncovered by movement past it of the left end of the enlarged piston portion. At this time air under pressure is still being supplied to the left end of air cylinder 50 through duct 51, so that part of this air will pass through the air cylinder and duct 54, as indicated by the broken line arrow, into the groove of valve block 7 farthest to the left. Although this groove communicates with the left atmospheric duct 75 through a small aperture, such aperture is sufficiently small so that a substantial pressure will be produced in this groove. Such air pressure will act upon the left end of such valve 70, which is exposed to the air in such groove, to overcome the pressure on right piston surface 77 and shift the valve to the right end of its stroke.

By such movement the central land of the valve will sever communication between air supply conduit 74 and duct 51, while simultaneously the left valve groove will be moved into registry with the valve block land immediately to the left of the central groove, so that air may bypass this land from air supply conduit 74 to duct 52. Such valve movement, therefore, has resulted in interrupting the supply of air under pressure to the left end of air cylinder 50 and supplying air under pressure to the right end of this cylinder.

At the same time this shifting of valve 70 moves its left land into sealing cooperation with the land between duct 52 and the left atmosphere duct 75, so that air under pressure can not pass directly from conduit 74 to such atmosphere duct, but must find its outlet through duct 52. On the contrary, duct 51, which previously did not communicate directly with atmosphere, now has an outlet to the right atmosphere duct 75 by way of the right valve groove around the valve block land separating the valve block grooves with which duct 51 and right duct 75 communicate, respectively.

Since the supply of air under pressure to the left end of air cylinder 50 has thus been interrupted, and instead a supply of compressed air to its right end established, while at the same time its left end has been vented to atmosphere, movement of the piston to the right will cease and it will be driven toward the left. During this movement air at first will be forced from the left end of the air cylinder through duct 54, exerting some pressure tending to hold valve 70 in its extreme right position, and air also will be forced out through duct 51.

Air passing through duct 54 will flow through the bleed orifice of the left valve block groove into the left atmospheric duct 75, while the air flowing through duct 51 will be discharged through the right atmospheric duct 75. Until piston 3 has moved to the left sufficiently so that its right

face passes beyond the opening of duct 53 into air cylinder 50 valve 70 will now be held in its right position by air under pressure passing from the central groove of valve block 7 through the left valve groove around the valve block land immediately left of center, and through the left valve aperture 76 to exert pressure upon the left inner valve shoulder 77. The right valve port 76 will, of course, communicate with the right atmospheric duct 75, so that the right inner valve shoulder 77 will be subjected only to atmospheric pressure.

During such movement of piston 3 to the left, the volume of the left hydraulic liquid cylinder 40 will be decreased by movement of piston plunger 30 into it. The increase in pressure on the oil will hold check valve 41 in the supply line S closed, but will open check valve 42 in the pressure line P. Such pressure will act upon check valve 62 in block 6 to close it and hold it closed, so that the oil under pressure will now be delivered from cylinder 40 to the pressure side of the drill feed mechanism through hose connection 23.

Simultaneously, of course, movement of piston plunger 31 out of hydraulic liquid cylinder 60 will increase its volume, so that since conduit P is closed cylinder 60 will be refilled with oil drawn from reservoir 13 through supply conduit S and past check valve 61. This operation will continue until the end of duct 53 opening into air cylinder 50 is again uncovered by the piston, whereupon valve 70 once more will be shifted to the left, by flow of air through duct 53, to reverse the piston stroke, as previously explained.

It will be appreciated that the reversal of piston 3 by automatic shifting of valve 70 in the manner explained will be effected instantaneously. Consequently, although delivered alternately from cylinders 40 and 60, oil will flow almost uninterruptedly from outlet 23, and because of its resilient nature, the hose connected to the outlet will expand under pressure and contract upon the tendency of the oil pressure to decrease sufficiently to maintain oil delivery to the drill at substantially constant pressure, to feed the drill continuously and smoothly. As oil is supplied to the pressure side of the drill feed mechanism oil will be discharged from its relief side through hose connection 24 and duct R of the pump back to reservoir 13. The rate of oil delivery may be governed as desired by throttling the flow of air to the pump piston 3 to regulate its speed of reciprocation. For this purpose a valve 78 may be adjusted to vary the size of the air inlet opening through passage 74.

Drain ducts D, one from oil cylinder 40 and the other from oil cylinder 60, drain back into the reservoir through return duct R oil which may be forced past plungers 30 and 31, respectively, and collect in grooves 43 and 63. Between these grooves and air cylinder 50 are additional grooves 44 and 64, respectively, vented to the atmosphere through a duct A which communicates through the groove of valve block 7 second from the left, from which groove the left atmospheric duct 75 leads. Air tending to blow by plungers 30 and 31 into cylinders 40 and 60, respectively, is thus released.

A problem in the actual construction of the pump unit was to make room for the various passages between the valve assembly and the air cylinder, and between the oil cylinders, the reservoir, and the supply and return connections, while at the same time incorporating all the parts in the cylindrical mine arm casing to the best ad-

vantage. In devising the pump mechanism the proper relative sizes of the several conduits had to be kept in mind as well as the problem of fabricating and assembling the various parts. To solve this problem the pump mechanism is composed of four cylindrical blocks, all of the same diameter and fitted together in end abutting engagement. Three of these blocks 4, 5 and 6 house the pump mechanism, and the fourth block 7 contains the valve mechanism.

As mentioned previously, the axis of the composite piston 3 is offset from the axis of the cylindrical blocks 4, 5 and 6 in which the piston and plunger cylinders are formed. Such eccentric disposition of the piston and cylinders provides space for the pressure supply duct S and return duct R, as shown in Figure 3. If desired, for a given diameter of the blocks 4, 5 and 6 a somewhat larger air cylinder 50 and larger oil ducts may be employed if the return and the suction ducts are combined. Instead of flowing into the reservoir 13, therefore, some of the oil may flow directly from the return connection 24 into the oil cylinders 40 and 60 through a single duct serving for both return and suction. The only change necessary in the construction shown would be to eliminate the passage R and to lead the port for connection 24 directly into the suction bore S of block 6. The space within the block could be utilized to better advantage, of course, if the bores were rearranged slightly in such event.

Because the body of the pump is formed in three parts the necessary bores may be drilled in the several blocks quite readily. Preferably block 4 has an end boss 45 and block 6 has an end boss 65 which will fit into the opposite ends of the air cylinder 50, as shown in Figure 1. This interengagement of the three blocks, in conjunction with the arm 1, itself constituting a casting, will locate all the passages in proper registry and relieve the reduced ends of piston 3 of all lateral load. Furthermore dowels 46, shown in Figure 3, may be employed as additional locating elements, if desired.

With the blocks 4, 5 and 6 all held in fixed relationship in the manner described, the keyway 14 extending throughout the length of these blocks will be straight, so that the locating pin 19 may hold them all in proper rotative position with relation to the mine arm 1. Before the valve block 7 is put in place a dowel pin 66 may be fitted into block 6 to interconnect these parts to hold them in registry for alignment of the cooperating sections of passages 51, 52, 53, 54 and A. When the screws 18 are now drawn up the blocks will all be clamped tightly together between shoulder 12 and the boss on block 17 fitting within the end of the mine arm. With the parts in this relationship air supply duct 74 will register with a passage through block 17 which communicates through the valve 78 with the air supply connection 79 attached to such block.

The convenience of such a pump assembly will be evident. Being carried by the mine arm, the only additional element required is the air supply connection 79 from any convenient source of compressed air. Normally this connection will be in the form of a hose, so that the arm 1 may be raised or lowered or rotated on the column B as desired merely by loosening clamp 10, adjusting the mine arm, and then again tightening it. Additionally the drill support 2 may be shifted outward along the mine arm, or inward almost to the column, because of the location of the sup-

ply and return fittings 23 and 24 close to the column, and the flexibility of the conduits between such supply and return connections and the drill. These hoses are short, so that they will not be in the way of the operator. Despite these advantages the pump is of adequate capacity to feed the drill effectively, and may be taken apart quickly whenever desired for cleaning, for repair or for replacement of parts.

I claim as my invention:

1. In combination, a mine column, tubular drill supporting means, a drill supported by said drill supporting means, a pump unit substantially housed within said tubular drill supporting means and conduit means interconnecting said pump unit and said drill for flow of fluid under pressure from said pump unit to said drill.

2. In combination, a mine column, a tubular mine arm extending laterally from said mine column, drill supporting means secured to said mine arm, a drill supported by said drill supporting means, a hydraulic pump unit housed within said mine arm, and conduit means interconnecting said pump unit and said drill for flow of liquid under pressure from said pump unit to said drill.

3. In combination, supporting means, a drill supported by said supporting means, a continuously rotatable, hydraulic drill-rotating motor connected to rotate said drill, an intermittent delivery hydraulic pump unit supported by said supporting means in a position adjacent to said drill rotating motor, and short resilient conduit means directly interconnecting said pump unit and said drill-rotating motor, and operable by reason of their resilience to deliver a constant flow of liquid to said drill-rotating motor under substantially constant pressure, although receiving liquid from said pump unit intermittently, thereby to effect substantially uniform rotation of said drill-rotating motor and said drill.

4. In combination, a mine column, a mine arm extending laterally from said mine column, drill supporting means secured to said mine arm, a drill supported by said drill supporting means, a double acting intermittent delivery hydraulic pump unit housed within said mine arm, and a short resilient hose interconnecting said pump unit and said drill, and operable by reason of its resilience to deliver a constant flow of liquid to said drill under substantially constant pressure, although receiving liquid from said pump unit intermittently.

5. In combination, a mine column, a mine arm extending laterally from said mine column and having a liquid reservoir in the end thereof remote from said mine column, drill supporting means secured to said mine arm, a drill supported by said drill supporting means, a hydraulic pump unit housed within the end of said mine arm adjacent to said mine column, and conduit means interconnecting said drill and the end of said mine arm adjacent to said mine column, and communicating with said pump unit for flow of liquid therefrom to said drill.

6. In combination, a mine column, a mine arm extending laterally from said mine column and having a liquid reservoir in the end thereof remote from said mine column, drill supporting means secured to said mine arm, a drill supported by said drill supporting means, an air driven hydraulic pump unit housed within the end of said mine arm adjacent to said mine column, conduit means interconnecting said drill and the end of said mine arm adjacent to said mine col-

umn, and communicating with said pump unit for flow of liquid therefrom to said drill, and means carried by the end of said mine arm adjacent to said mine column operatively connected to said pump unit for regulating the supply of air thereto to vary the delivery of liquid therefrom to said drill at will.

7. A pump unit comprising a generally cylindrical casing having a reservoir in one end thereof, a generally cylindrical control valve body fitting closely within the opposite end of said casing, air control valve means in said control valve body, a generally cylindrical pump body interposed between such reservoir and said control valve body and having a pump chamber therein, pump means in such pump chamber, and air motor means in said pump body and operatively connected to said pump means to drive the same, said pump body and said control valve body having air ducts therein establishing communication between said control valve means and said air motor means, and said pump body having ducts therein establishing communication between the reservoir and the pump chamber, and forming a delivery passage for discharge of liquid under pressure from the pump chamber.

8. A pump unit comprising a generally cylindrical pump body having a pump chamber therein, pump means in such pump chamber, air motor means in said pump body and operatively connected to said pump means to drive the same, said pump body having air ducts extending therethrough for supplying air to said air motor means for operating the same, a cylindrical control valve body disposed substantially in axial alignment with said pump body, and air control valve means in said control valve body, said control valve body having air ducts therein establishing communication between said air control valve means and such air ducts in said pump body for controlling the supply of air to said air motor means, and said pump body having therein further ducts communicating with such pump chamber for supplying liquid thereto and for delivery of liquid under pressure therefrom.

9. A pump unit comprising an elongated pump body having therein a cavity elongated lengthwise of said pump body and disposed eccentrically thereof, a double acting pump element reciprocably received within such cavity and disposed generally midway between the ends thereof to define a pump chamber at each end of the pump body cavity, means operable to reciprocate said pump element, a liquid reservoir adjoining said pump body, and duct means disposed wholly within and extending lengthwise through said pump body alongside such elongated cavity adapted to communicate with both of such pump chambers for supply of liquid thereto, and opening directly into said reservoir.

10. A pump unit comprising a generally cylindrical pump body having therein a generally cylindrical cavity with its axis offset to one side of the axis of said pump body, a pump element reciprocable axially of such cavity and received generally midway between the ends thereof to define a pump chamber at each end of the pump body cavity, means operable to reciprocate said pump element, and duct means extending lengthwise through said pump body offset generally to the opposite side of its axis from the axis of the pump body cavity, and adapted to communicate with both pump chambers for flow of fluid between said duct means and both of said pump chambers.

11. In combination, a mine column, a mine arm extending laterally from said mine column and having a liquid reservoir in the end thereof remote from said mine column, drill supporting means secured to said mine arm, a drill supported by said drill supporting means, a cylindrical pump body fitting closely within the end of said mine arm adjacent to said mine column, and having therein a generally cylindrical pump chamber with its axis offset to one side of the axis of said pump body, pump means in such pump chamber, a delivery conduit and a return conduit interconnecting said drill and the end of said mine arm adjacent to said mine column, and duct means offset generally to the side of the pump body axis opposite the pump chamber axis, and establishing communication between the reservoir, the pump chamber, and said conduits, for supplying liquid to the pump chamber, delivering liquid under pressure therefrom to said drill through said delivery conduit, and for return of liquid from said drill to the reservoir through said return conduit.

12. In combination, a mine column, a cylindrical mine arm extending laterally from said mine column and having a liquid reservoir in the end thereof remote from said mine column, drill supporting means secured to said mine arm, a drill supported by said drill supporting means, a cylindrical pump body fitting closely within the end of said mine arm adjacent to said mine column, and having therein a generally cylindrical pump chamber with its axis offset to one side of the axis of said pump body, double acting pump means in such pump chamber, and a resilient delivery conduit and a return conduit interconnecting said drill and the end of said mine arm adjacent to said mine column, said pump body having ducts therethrough offset generally to the side of its axis opposite the pump chamber axis, and establishing communication between the reservoir, the pump chamber, and said conduits, for supplying liquid to the pump chamber, delivering liquid under pressure therefrom to said delivery conduit and for return of liquid from said drill to the reservoir through said return conduit, said delivery conduit operating by reason of its resilience to deliver a constant flow of liquid to said drill under substantially constant pressure although receiving liquid from the pump body ducts intermittently.

13. A pump unit comprising a pump body including three cylindrical blocks disposed in axial alignment, the central block having therein an air chamber and the blocks at opposite ends thereof each having therein a pressure liquid chamber, all such chambers being disposed in alignment, a composite piston having portions slidably fitting in each of such chambers, a cylindrical valve body disposed in axial alignment with said pump body, and automatic reversing air valve means in said valve body, said pump body and said valve body having registering air ducts therethrough establishing communication between said valve means and the air chamber of the central pump body block, and said pump body having therethrough a passage communicating with each of the pressure liquid chambers for discharge of liquid under pressure therefrom.

14. A pump unit comprising a cylindrical casing having a liquid reservoir in one end thereof, a pump body including three cylindrical blocks disposed in axial alignment and fitted closely within said cylindrical casing, the central block having therein an air chamber and the blocks at oppo-

site ends thereof each having therein a pressure liquid chamber, all such chambers being disposed in alignment, a composite piston having portions slidably fitting in each of such chambers, a cylindrical valve body disposed in axial alignment with said pump body at the end thereof remote from the reservoir, and automatic reversing air valve means in said valve body, said pump body and said valve body having registering air ducts therethrough establishing communication between said valve means and the air chamber of the central pump body block, and said pump body having passages therethrough establishing communication between the reservoir and both of the pressure liquid chambers, and defining a passage communicating with each of the pressure liquid chambers for discharge of liquid under pressure therefrom.

15. In combination, a mine column, a cylindrical mine arm extending laterally from said mine column, and having a liquid reservoir in the end thereof remote from said mine column, drill supporting means secured to said mine arm, a drill supported by said drill supporting means, a pump body including three cylindrical blocks disposed in axial alignment and fitted closely within said cylindrical mine arm adjacent to said mine column, the central block having therein an air chamber, and the blocks at opposite ends thereof each having therein a pressure liquid chamber, all such chambers being disposed in alignment and their axes being offset to one side of the axis of said pump body, a composite piston having portions slidably fitted in each of such chambers, a cylindrical valve body disposed in axial alignment with said pump body and at the end thereof remote from the reservoir, automatic reversing air valve means in said valve body, and a delivery conduit and a return conduit interconnecting said drill and the end of said mine arm adjacent to said mine column, said pump body and said valve body having registering air ducts therethrough establishing communication between said valve means and the air chamber of the central pump body block, and said pump body blocks having passages therethrough offset generally to the side of their axis opposite the axis of their chambers and establishing communication between the reservoir, said conduits, and both of the pressure liquid chambers, for supplying liquid to the pressure liquid chambers from the reservoir, delivering liquid under pressure from the pressure liquid chambers to said delivery conduit, and for return of liquid from said drill to the reservoir through said return conduit.

16. A pump unit comprising a tubular casing having a reservoir therein, a pump body fitted within said tubular casing, and having two pump chambers therein, two interconnected pump elements one movable in each of said pump chambers, motor means housed within said casing and operable simultaneously to drive one of said interconnected pump elements into its pump chamber and to withdraw the other of said pump elements outwardly relative to its pump chamber, and duct means establishing communication between such reservoir and both of such pump chambers, and further affording a delivery passage communicating with both pump chambers for alternate discharge of liquid therefrom, and a return passage communicating with the reservoir for return of liquid thereto.

17. A pump unit comprising a tubular casing having a reservoir therein, a pump body fitted

within said tubular casing, and having two pump chambers therein one adjacent to each end thereof, two interconnected pump elements one movable in each of said pump chambers, motor means housed within said casing intermediate said two pump chambers and operable simultaneously to drive one of said interconnected pump elements into its pump chamber and to withdraw the other of said pump elements outwardly relative to its pump chamber, and duct means establishing communication between such reservoir and both of such pump chambers, and further affording a delivery passage communicating with both pump chambers for alternate discharge of liquid therefrom, and a return passage communicating with the reservoir for return of liquid thereto.

HENRY S. HOFFAR.

Certificate of Correction

Patent No. 2,416,317.

February 25, 1947.

HENRY S. HOFFAR

It is hereby certified that error appears in the printed specification of the above numbered patent requiring correction as follows: Column 9, line 11, claim 1, strike out "a mine column,"; and that the said Letters Patent should be read with this correction therein that the same may conform to the record of the case in the Patent Office.

Signed and sealed this 13th day of May, A. D. 1947.

[~~SEAL~~]

LESLIE FRAZER,
First Assistant Commissioner of Patents.
